(57) **CLAIM**

The ornamental design for a fluid pressure cylinder with plate, as shown and described.

DESCRIPTION

FIG. 1 is a top, front and left-side perspective view of a fluid pressure cylinder with plate showing a first embodiment of my new design;

FIG. 2 is a front view thereof;
FIG. 3 is a rear view thereof;
FIG. 4 is a top plan view thereof;
FIG. 5 is a bottom plan view thereof;
FIG. 6 is a left side view thereof;
FIG. 7 is a right side view thereof;
FIG. 8 is a top, front and left-side perspective view of a fluid pressure cylinder with plate showing a second embodiment of my new design;
FIG. 9 is a front view thereof;
FIG. 10 is a rear view thereof;
FIG. 11 is a top plan view thereof;
FIG. 12 is a bottom plan view thereof;
FIG. 13 is a left side view thereof;
FIG. 14 is a right side view thereof;
FIG. 15 is a top, front and left-side perspective view of a fluid pressure cylinder with plate showing an third embodiment of my new design;
FIG. 16 is a front view thereof;
FIG. 17 is a rear view thereof;
FIG. 18 is a top plan view thereof;
FIG. 19 is a bottom plan view thereof;
FIG. 20 is a left side view thereof;
FIG. 21 is a right side view thereof;
FIG. 22 is a top, front and left-side perspective view of a fluid pressure cylinder with plate showing a fourth embodiment of my new design;
FIG. 23 is a front view thereof;
FIG. 24 is a rear view thereof;
FIG. 25 is a top plan view thereof;
FIG. 26 is a bottom plan view thereof;
FIG. 27 is a left side view thereof;
FIG. 28 is a right side view thereof;
FIG. 29 is a top, front and left-side perspective view of a fluid pressure cylinder with plate showing a fifth embodiment of my new design;
FIG. 30 is a front view thereof;
FIG. 31 is a rear view thereof;
FIG. 32 is a top plan view thereof;
FIG. 33 is a bottom plan view thereof;
FIG. 34 is a left side view thereof; and,
FIG. 35 is a right side view thereof.

(Continued)

The portions of the fluid pressure cylinder with plate shown in broken lines form no part of the claimed design.
